CONDENSER CONSTRUCTION

Raymond A. Lane, Elmhurst, N. Y., assignor to
 Products Protection Corporation, a corporation
 of Delaware

Application May 23, 1930. Serial No. 455,072

14 Claims. (Cl. 175--41)

This invention relates to electric condenser construction.

One of the objects of this invention is to provide a compact condenser construction having a high capacity per unit volume. Another object is to provide an electric condenser that will be of highly efficient action, well adapted for use in operation on circuits of relatively high potential, inexpensive to manufacture, and well adapted for long-continued practical use. Another object is to provide a condenser construction which may be standardized as to the size and shape of various of its parts so as to minimize cost of manufacture and facilitate ease of assembly, all, however, without detracting from dependability and high efficiency of action in practical use. Another object is to provide a high voltage electric condenser construction in which insulation problems are vastly minimized. Another object is to provide a high voltage condenser in which thoroughly dependable and efficient insulation is achieved in a practical and inexpensive manner. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of various possible embodiments of my invention,

Figure 1 is a vertical sectional view, certain parts being shown in elevation,

Figure 2 is a horizontal sectional view, as seen along the line 2--2 of Figure 1, and

Figure 3 is a detached vertical sectional view, on an enlarged scale, taken transversely of one of the interconnecting conductors shown in Figure 2.

Similar reference characters refer to similar parts throughout the several views of the drawings.

Referring now to the drawings, there is shown at 10 a tank or casing, preferably a pressed steel tank, capable of withstanding substantial pressure; this tank is preferably of generally cylindrical shape, as appears from Figure 2, and is provided with a closure member 11, carrying a high voltage terminal 12 substantially at its center, and adapted, after the condenser construction described in detail below has been inserted into the casing 10, to be welded to the latter as at 13. The terminal 12 may be of any suitable

construction for passing the high tension conductor, leading to the high tension terminal of the condenser within the container, through the metal wall formed by the closure member 11.

As for the condenser construction, I prefer to build the latter in the form of sections and by way of illustration I have shown the condenser, in the drawings, as made up of seven sections, namely, sections 14, 15, 16, 17, 18, 19 and 20. It will be understood, however, that a greater or lesser number of sections may be employed.

In so far as certain features of my invention are concerned, the condenser elements that go to make up each section may be of any desired or suitable construction but preferably each section is made up of rectangularly shaped sheets of metal foil alternated with a suitable solid dielectric material in sheet form, such as a suitable paper. A suitable number of foil plates (not shown in the drawings) are embodied in each section, insulated, of course, from each other, and connected together in any suitable manner so that each section, as will be more clearly described hereinafter, will have two terminals to permit electrical connection to be made to the sections.

The sections 14, 15, 16, etc. generally rectangular in shape and of a thickness depending upon various factors such as the number of foil plate members therein, the thickness of the sheet insulating material, and the like, are arranged flatwise against each other, adjacent sections being separated by suitable solid dielectric barriers, made, for example, of press-board, and indicated at 21.

Against the outer face of the end section 14 is laid a rigid metal plate 22, a suitable sheet 23 of solid dielectric material, like press-board, being interposed therebetween. Similarly a rigid metal plate 24 is laid against the outer face of the opposite end section 20 with a sheet of insulation 25 interposed therebetween.

The thus far assembled condenser sections are thereupon tightly compressed and held in compressed and assembled relation by means of upper and lower bolts 26 and 27, having their ends passed through angle iron members 28 that extend crosswise of the metal plate members 22 and 24 and having their ends projecting sufficiently above and below the assembled condenser sections as will cause the tie bolts 26 and 27 adequately to be sufficiently spaced from the aligned condenser sections. The tie bolts 26 in coaction with the angle iron members 28 and the end plates 22

and 24 thus hold the condenser sections in tightly compressed and assembled relation.

The thus assembled condenser sections are thereupon inserted into the casing 10, through the upper open end thereof, whereupon, after certain connections described hereinafter have been made, the closure member 11 is welded in place to hermetically seal the condenser within the tank or casing 10.

10 As above noted, each condenser section is provided with suitable connecting terminals and these are preferably brought out of the respective sections at points in their vertical end faces, as viewed in Figure 1.

15 In order to make clearer the manner of interconnecting of the different condenser sections, let it be assumed that the condenser is to operate on a circuit of 35000 volts, one side of which circuit is grounded. Let it further be assumed that 20 each section of the condenser, there being illustratively seven sections, is constructed to withstand and operate at a potential of 5000 volts. In the operation of the condenser, therefore, each section will account for a reactance drop of 5000 25 volts, the reactance drop across the entire condenser being 35000 volts, the assumed voltage of the circuit in which the condenser is to operate.

One terminal 14^a of the end section 14, which, as viewed in Figure 2, will be seen to be nearest 30 the lowermost side portion of the side walls of the casing 10, is grounded, as by conductor 29, to the container 10; the other terminal 14^b (see Fig. 1), at a potential of 5000 volts, is connected by a conductor 30 to the outermost terminal 20^a of 35 the other end section 20 which, as viewed in Figure 2, is the section that is nearest the uppermost side portion of the wall of the container 10. The other terminal 20^b of the section 20, this terminal being at a potential of 10,000 volts, is connected by conductor 36 to terminal 15^a of section 15 which is the section adjacent the opposite end section 14.

The other terminal 15^b of the section 15, this terminal being at a potential of 15000 volts, is 45 connected by conductor 31 to one terminal 19^a of the section 19 which is adjacent the opposed end section 20.

The other terminal 19^b of the section 19, this terminal being at a potential of 20,000 volts, is 50 connected by conductor 32 to a terminal 16^a of the section inwardly adjacent of the section 15; the other terminal 16^b, at a potential of 25,000 volts, is connected by conductor 33 to terminal 18^a of the section 17 next adjacent, in an inward direction, to the section 19.

The other terminal 18^b, at a potential of 30,000 60 volts, is connected by conductor 34 to one terminal 17^a of the middle section 17 which also is the section adjacent, in an inward direction, to the section 16. The section 17 adds 5,000 volts to the series circuit thus being traced and hence the other terminal 17^b of the section 17 will be at a potential of 35,000 volts. This terminal 17^b, however, is preferably taken out of the section 17 in its upper end face (see Fig. 2) whence a conductor 35 connects it to the conductor of the high voltage terminal 12.

Relative to the casing, the highest potential effective in the one end section 14 is 5,000 volts; hence the insulation, such as the press-board member 23, that I need provide between the section 14 and the adjacent side wall portion of the casing 10 need be effective only for this voltage. The highest potential effective in the section 20, relative to the casing 10, is 10,000 volts, and

hence the insulation, such as the press-board member 25, between that and section 20 and the adjacent side wall portion of the casing 10 need be effective to withstand only 10,000 volts.

The highest potential effective in the section 15 will be 15,000 volts, relative to the casing 10, but it will be noted that this section is, by reason of its interconnection with respect to the other sections, positioned more remotely from the end wall section, having, in fact, interposed between it and the latter the condenser section 14.

The highest potential effective in the section 19 will be 20,000 volts, relative to the other or opposed side wall portions of the casing 10, but, as will be clear from the drawings, the section 19 finds itself spaced inwardly from the side wall portion to a greater extent than is the end section 20.

In like manner section 16, then section 18, and finally section 17, the latter of highest potential relative to the casing, find themselves progressively more distant from the opposed side wall portions of the casing 10.

Thus it will be noted that, as the potentials of the sections relative to the casing increase, they are positioned proportionately more remote from the casing wall and even though there is effective in the apparatus a potential as high as 35,000 volts under the above-assumed illustrative practical conditions, any single insulating barrier anywhere in the condenser construction need withstand a potential of only 10,000 volts, that being the potential difference between the end section 20 and the adjacent side portion of the casing wall and that being the potential difference between any two adjacent sections. The press-board barriers 21 and 25 therefore need be constructed to withstand safely only 10,000 volts, though parts of the apparatus actually function at a voltage greatly in excess of that figure.

The sealed casing 11 is filled preferably with a gaseous dielectric under pressure, such as nitrogen under a pressure on the order of fifteen atmospheres, and this gaseous dielectric under pressure serves to coat with certain of the solid dielectric media employed to effect an unusually efficient insulation, certain features of which will be described hereinafter.

The connecting conductors 30, 36, 31, 32, 33 and 34 will be seen to be displaced vertically, as is clearly shown in Figure 1, and they, moreover, are positioned in the segment-like space between the aligned right-hand ends (see Figure 2) of the condenser sections and the adjacent curved wall of the casing 10. Preferably these connectors, which are preferably covered with a solid dielectric material as is indicated in Figure 3, where one of these conductors with its insulating covering is shown in cross-section spaced from the container wall, are curved, in a manner generally indicated in Figure 2, and they are, moreover, so shaped that, as they cross-connect condenser sections to either side of the middle section 17, they are progressively more distantly spaced from the condenser as their potentials relative to the condenser sections which they have to jump over increase and so that, also, as their potentials relative to the casing 10 increase, their spacings from the latter progressively increase.

By way of example, the connector 30, at a potential of 5,000 volts as above noted, is most closely positioned to the curved side wall of the casing 10 but it is so bent or looped that its spacing from the middle section 17 (which is at a potential of 35,000 volts) is relatively great. The con-

5 nector 36, at a potential of 10,000 volts relative to the casing 10, is spaced a greater distance from the curved wall of the casing while it is more closely spaced to the voltage section between which and itself there exists a potential difference of 25,000 volts.

10 The gaseous dielectric under pressure coacts with the solid dielectric coverings on the above-mentioned connectors to make it possible to diminish the above-mentioned spacings materially and to make it possible to use a lesser amount 15 of solid dielectric material covering the connectors themselves.

Recurring now to the insulation of the individual condenser sections from the casing 10 itself, it might first be again noted that the potential differences between the sections and the casing 10, referring now to Figure 2, increase in a direction from the section 14 to the section 17 20 and from the section 20 to the section 17; these right-hand and left-hand portions of the casing 10, still as viewed in Figure 2, or, more clearly, those opposed portions of the side wall of the casing 10 that are subtended by the chords forming the alined vertical edges of the alined sections 25 are progressively more distant from these sections as the potential differences above noted increase. The spacing between these portions of the side walls and the vertical edges of the alined sections are filled with the gaseous dielectric under 30 pressure and thus the thickness of the layer of this gaseous dielectric under pressure increases substantially in proportion to the increasing potential differences between the sections and the 35 side wall portions of the casing.

Thus a thoroughly dependable insulation of the sections of higher voltage not only from each other and from sections of lower voltage but also from the casing itself is dependably achieved, 40 not only in a vertical direction, as viewed in Figure 2, but also in a horizontal direction, as viewed in this figure. Moreover, these advantages will be seen to be achieved with apparatus of exceedingly simple construction and arrangement and, 45 moreover, apparatus that lends itself readily to inexpensive and rapid manufacture.

It will thus be seen that there has been provided in this invention a condenser construction in which the various objects above noted, together with many thoroughly practical advantages are successfully achieved. It will be seen that the apparatus is of a thoroughly practical nature, is well adapted to operate at relatively high potentials, has a high capacity per unit volume and achieves highly efficient insulation with a minimum of insulating media.

As many possible embodiments may be made of the above invention and as many changes might be made in the embodiment above set forth, 55 it is to be understood that all matter hereinbefore set forth, or shown in the accompanying drawings, is to be interpreted as illustrative and not in a limiting sense.

I claim:

60 1. In condenser construction, in combination, a casing having opposed side wall portions, a condenser made up of sections alined between said opposed side wall portions, and means cross connecting sections lying to either side of a middle section so that the endmost sections, respectively adjacent said side wall sections, are of relatively lowest potential, and a middle section of highest potential, and intervening sections of progressively increasing potential as said middle section 65 is approached.

2. In condenser construction, in combination, a casing having opposed side wall portions, a condenser made up of sections alined between said opposed side wall portions, a high voltage terminal having its conductor connected to a middle section, means grounding an end section to said container, means connecting the other terminal of said end section to a terminal of the other end section, means connecting the other terminal of said other end section to a terminal of a section adjacent said first-mentioned end section, means connecting the other terminal of said adjacent section to a terminal of a section adjacent said other end section, and means connecting the other terminal of said last-mentioned adjacent section to the other terminal of said middle section. 80

3. A condenser construction, in combination, a container having side wall portions, a condenser made up of sections arranged in substantial alinement between said side wall portions, a high voltage terminal having its conductor connected to a terminal of a middle section so that said middle section is of highest potential, and means alternately connecting in series sections to either side of and progressively more remote from said middle section. 90

4. In condenser construction, in combination, a container, and a high voltage condenser therein and made up of sections serially connected in alternation about a middle section so that the potential differences between sections and said container vary, said container having a wall shaped so that the spacing thereof in a direction lengthwise of said sections varies in accordance with the potential differences between said sections and said wall. 100

5. In condenser construction, in combination, a container, and a high voltage condenser therein and made up of sections serially connected in alternation about a middle section so that the potential differences between sections and said container vary, said container having a wall shaped so that the spacing thereof in a direction lengthwise of said sections varies in accordance with the potential differences between said sections and said wall. 110

6. In condenser construction, in combination, a container having side wall portions, a condenser made up of sections arranged substantially in alinement between said side wall portions, and means connecting all of said sections in series so that a middle section is of highest potential, end sections adjacent said side wall portions of relatively lowest potential, and sections intermediate of said middle section and said end sections will be of potentials intermediate of said highest and said relatively lowest potentials. 125

7. In condenser construction, in combination, a container having side wall portions, a condenser made up of sections arranged substantially in alinement between said side wall portions, and means connecting all of said sections in a single series circuit starting from an inner section and progressively including the more outward sections, the spaced relation between container and condenser being such that the sections have a potential substantially proportionate to their respective distances from the nearest side wall portion. 140

8. In condenser construction, in combination, a substantially cylindrical casing, a condenser with in said casing and made up of a plurality of se- 145 150

rially connected sections, said sections being of substantially the same size and alined and having their planes extending parallel to the axis of said cylindrical casing, and means connecting 5 said sections so that the potentials, relative to said casing, of said sections progressively increase in a direction from the endmost sections to a middle section.

9. In condenser construction, in combination, a 10 substantially cylindrical casing, a condenser within said casing and made up of a plurality of sections, said sections being of substantially the same size and alined and having their planes extending parallel to the axis of said cylindrical casing, and 15 connectors, positioned in the segment-shaped space between the curved side wall of said casing and said alined sections for progressively and alternately cross-connecting sections to either side of a middle section of said condenser so that 20 the sections more remote from said middle sections are of progressively lower potentials.

10. In condenser construction, in combination, a substantially cylindrical casing, a condenser within said casing and made up of a plurality of 25 sections, said sections being of substantially the same size and alined and having their planes extending parallel to the axis of said cylindrical casing, and connectors, positioned in the segment-shaped space between the curved side wall of said 30 casing and said alined sections for progressively and alternately cross-connecting sections to either side of a middle section of said condenser so that the sections more remote from said middle sections are of progressively lower potentials, 35 said connectors being insulated from the wall of said casing by solid dielectric material arranged in series with gaseous dielectric under pressure.

11. In condenser construction, in combination, a substantially cylindrical casing, a condenser 40 within said casing and made up of a plurality of sections, said sections being of substantially the same size and alined and having their planes extending parallel to the axis of said cylindrical casing, connectors, positioned in the segment-shaped space between the curved side wall of said 45 casing and said alined sections for progressively and alternately cross-connecting sections to either side of a middle section of said condenser so that the sections more remote from said 50 middle sections are of progressively lower potentials, and a gaseous dielectric under pressure fill-

ing said segment-shaped space and said connectors being immersed therein.

12. In condenser construction, in combination, a substantially cylindrical casing, a condenser within said casing and made up of a plurality of sections, said sections being of substantially the same size and alined and having their planes extending parallel to the axis of said cylindrical casing, and connectors, positioned in the segment-shaped space between the curved side wall of said casing and said alined sections for progressively and alternately cross-connecting sections to either side of a middle section of said condenser so that the sections more remote from said middle sections are of progressively lower potentials, said connectors being so spaced from the wall of said casing that the spacing increases as the potentials of said connectors increase. 80

13. In condenser construction, in combination, a container having opposite side wall portions, a condenser made up of a plurality of plate elements, the planes of which extend transversely to a line joining said opposed side wall portions, and means connecting all of said plate elements in a single series circuit starting from an inner section and progressively including the more outward sections, the spaced relation between container and condenser being such that the plate elements have a potential relative to the casing substantially proportionate to their respective distances from the nearest side wall portion. 95

14. In condenser construction, in combination, a container having opposed side wall portions and opposed end wall portions, a condenser made up of a plurality of plate elements the planes of which extend substantially transversely to a line connecting said opposed side wall portions, said end wall portions and said condenser elements being shaped with respect to each other so that the spacing between said end wall portions and the adjacent edge portions of said plate elements increases in a direction from each side wall portion toward substantially the middle plate element of said condenser, and means connecting all of said plate elements in a single series circuit so 110 that the plate elements have potential differences relative to said casing substantially proportional to their respective shortest distances from the nearest side wall portion and end wall portion. 115
